UNITED STATES PATENT OFFICE.

MAXILLIAM E. PRIMBS, OF PITTSBURGH, PENNSYLVANIA, ASSIGNOR OF ONE-FOURTH
TO CHARLES W. LAMPUS, OF PITTSBURGH, PENNSYLVANIA.

TIMER.

1,326,781.

Specification of Letters Patent. Patented Dec. 30, 1919.

Application filed February 13, 1917. Serial No. 148,373. Renewed June 27, 1919. Serial No. 307,256.

To all whom it may concern:

Be it known that I, MAXILLIAM E. PRIMBS, a citizen of the United States residing at Pittsburgh, in the county of Allegheny and State of Pennsylvania, have invented new and useful Improvements in Timers, of which the following is a specification.

This invention relates to a timer and more particularly to the construction of a timer to replace the well known "Ford" timer and has for its primary object to provide a timer having a number of improved features over the "Ford" timer.

15 An object of the invention is the provision of a timer, the commutator of which may be readily replaced with a minimum amount of expense and by an inexperienced person.

20 Another object of the invention is the novel manner of construction and assembling the parts so that a relatively small portion of the device will be thrown away when the commutator is worn out.

25 Another feature of the invention is the novel manner of permanently connecting the lead wires to a permanent member within the timer and the simple manner of associating the member with the commutator.

30 Besides the above my invention is distinguished in the manner of associating the cap with the commutator and casing so that the segments of the commutator will be properly associated with the contacts of the ring and upon removal of one of the pins the driver is capable of completely rendering the timer useless.

35 A further feature of my invention is the novel manner of housing the lead wires so that the same will not be subjected to wear or the action of oils.

With these and other objects in view the invention will be better understood from the following detail description taken in connection with the accompanying drawings wherein:

Figure 1 is a side elevation of an end plate of an engine showing my invention applied thereto.

40 Fig. 2 is a vertical sectional view thereof.

Fig. 3 is a front elevation of the timer with the cap removed.

45 Figs. 4 and 5 are detail side elevations of the rings.

50 Figs. 6 and 7 are sectional views through the rings.

Fig. 8 is an enlarged sectional view showing the coöperation between the contacts and segments.

Figs. 9 and 10 are detail views of a segment.

Fig. 11 is a perspective view of a contact.

Fig. 12 is a detail sectional view of the upper end of the extension. 65

My invention consists of a casing 1 shown in this particular instance of an annular shape with a tangentially arranged hollow extension 2 communicating with the interior of the casing. The casing is provided with an inwardly extending annular flange 3. Slidably mounted within the casing so as to move toward and away from the flange 3 to form an annular recess 4 is a ring 5 also provided with an annular flange 6 having bearing on the flange 3. 70

Supported by the ring 5 are contacts 7 having extensions 8 projecting through the flange so as to be permanently attached to the ends of the lead wires as indicated at 9. 80

It is of course to be understood that there are as many contacts as there are engine cylinders and each contact is secured to a lead wire although only one is shown in Fig. 5. 85

Slidably supported within the ring 5 is a second ring 10. The exact construction of the ring is such that the ring proper slides within the flange 6 while an annular flange 11 slides within the ring proper 5. Thus it 90 will be seen that the sliding movement of the rings toward each other is limited. The ring 10 and the segments 12 form the commutator of the invention and each segment is provided with an extension 13 passing through the flange 11 and arranged to act against a contact 7. 95

As far as I have proceeded it will be seen that the connections of the lead wires and contacts are permanent and a quick detachable connection will be accomplished between the contacts and segments. When the commutator is worn out it is only necessary to remove the ring 10 and replace by a new ring. By this action the connections of the 100 lead wires are not subjected to a strain.

For the purpose of partly rotating the ring 10 within the ring 5 for advancing and retarding the spark and also to insure the proper engagement between the segments 110 and contacts I provide a cap 14 of the usual shape now used upon a "Ford". The dif-

ference between the cap on the "Ford" and my cap is that my cap is detachably associated with the other elements of the timer by lugs 15 that enter correspondingly shaped openings in the ring 10. The cap has secured thereto a control arm 16 of the controlling device 17.

Pins 18 and 19 are mounted in the casing in the path of movement of the arm 16 so as to limit the rotatable action of the cap and ring 10 and as the lugs 15 are properly portioned with the arm upon the ring 10 and with relation to the engaging action between the segments and contacts, it will be seen that the pins 18 and 19 will positively prevent complete disengagement between the segments and contacts. Should it become advisable in practice the pin 19 can be removably associated with the casing so that a well informed driver under certain conditions can remove the pin 19 and by operating the control device at the proper time break connection between the segments and contacts and thus render the ignition inactive.

Referring to Fig. 12 of the drawing it will be seen that the extension 2 has its end formed into a head 20 in which is seated a terminal block 21 including sockets 22 that are adapted to be connected to the lead wires and to have a detachable connection with the plugs 23 forming the terminals for the ignition wires.

To complete my invention I use the spring clamp 24 for clamping the various parts together. Upon the removal of the clamp 24 the various parts of my invention can be quickly and readily disconnected.

It is to be understood that while all of the several parts of my improved timer have special cooperation with one another and together constitute a particularly effective mechanism for the purpose in view certain of these features may be applied in other relations and I therefore desire to cover the combinations present in the several parts of my improved mechanism whether employed in the general organization shown or elsewhere.

It is to be understood that the structural embodiment of the invention as a whole and its various features as shown is merely illustrative and not restrictive since I am well aware that many of the details of construction can be widely varied without departing from the spirit of the invention. I therefore do not desire to be limited in these particulars or in any others except as set forth in the appended claims.

What I claim is:—

1. In a timer a cylindrical casing having a tangentially arranged hollow extension lead wires arranged in the extension, a ring slidably mounted within the casing and co-

operating with the latter to form a recess 65 for the reception of the ends of the lead wires, contacts supported by the ring and permanently connected to the lead wires and a commutator consisting of a ring slidably mounted in the first ring and segments arranged 70 to bear upon said contacts, a cap having a slidably detachable connection with the second ring, a control arm projecting therefrom and means carried by the casing and arranged in the path of movement of 75 the arm for limiting the rotatable movement of the cap.

2. A timer embodying a cylindrical casing, an annular flange therein, a ring located within said casing and spaced from 80 said flange to define an annular chamber, conductor plates extending through openings in the ring into said chamber, lead wires extending into said chamber for connection with the conductor plates, a second ring 85 within the first mentioned ring, commutator segments mounted within said second ring for limited rotary movement and bearing against the conductor plates and a rotary driven element adapted to successively engage the commutator segments.

3. A timer embodying a cylindrical casing, an annular flange therein, a ring located within said casing and spaced from 95 said flange to define an annular chamber, conductor plates extending through openings in said ring into said chamber, lead wires also extending into said chamber for connection to the conductor plates, a second ring mounted within the first mentioned ring 100 and capable of limited relative rotation, segmental commutator plates secured within the second mentioned ring and extending through openings in the latter for contact with the conductor plates and a rotary 105 driven element adapted to successively engage the commutator plates.

4. A timer embodying a cylindrical casing, an annular flange therein, a ring located within said casing and spaced from 110 said flange to define an annular chamber, conductor plates extending through openings in said ring into said chamber, lead wires also extending into said chamber for connection to the conductor plates, a second ring mounted within the first mentioned ring 115 and segmental commutator segments located upon the inner periphery of the second mentioned ring, radially extending arms carried by said commutator segments, said 120 arms extending through openings in the last mentioned ring for wiping engagement with the conductor plates and a rotary driven element adapted to successively engage the commutator segments.

In testimony whereof I affix my signature.

MAXILLIAM E. PRIMBS.
